UNITED STATES PATENT OFFICE.

FRED R. COATS AND JEAN F. HARTWELL, OF SPRINGFIELD, ILLINOIS.

DEPTH-ADJUSTER FOR WATCH-ESCAPEMENTS.

1,368,118.

Specification of Letters Patent.

Patented Feb. 8, 1921.

Application filed March 10, 1920. Serial No. 364,725.

To all whom it may concern:

Be it known that we, FRED R. COATS and JEAN F. HARTWELL, citizens of the United States, residing at Springfield, in the county 5 of Sangamon and State of Illinois, are joint inventors of the Depth-Adjusters for Watch-Escapements, of which the following is a specification.

The invention relates to means for adjustment of the depth of engagement between the escape wheel and the cylinder staff or pallet used with lever escapement watches. We have shown and will describe a preferred embodiment of our invention 10 as applied to a cylinder escapement but obviously it may be applied, with equal advantage, to a lever escapement.

The invention is illustrated in the annexed drawing to which reference is hereby 20 made, and in which Figure 1 is a bottom plan of the pillar plate of a watch and the improved adjusting device in place thereon; and Fig. 2 is a vertical section on the line 2—2 of Fig. 1. The same reference numerals 25 designate the same parts in both the views.

To attain accurate adjustment of the cylinder staff relative to the escape wheel with which it cooperates, we provide means now 30 to be described.

Suitably located in the pillar plate 1 are the cylinder staff opening 2 in line with the cylinder staff 3, a trench 4 in which an adjusting arm 5 is oscillative and a circular 35 boss-opening 6, in which the circular-boss 7 of the arm is fitted, so that the boss will rotate accurately in the opening. The balance cock 18 has holes 8 matching dowel pins 9 on the boss and a hole 10 accommodating a screw 12 which screws into the boss and clamps the balance cock on the boss. The arm 5 has an arcuate slot 13. A screw 40 45 extends through the slot and screws into the pillar plate to clamp the arm on the plate. The slot 13 is of suitable length to permit transverse movement of the arm within the scope of the trench 4. A jewel 15 at the free end of the arm is in line with a jewel 16 near the outer end of the balance 50 55 cock, and the pivots of the cylinder staff bear in the respective jewels. An adjusting screw 17 screws into the pillar plate and its inner end engages on the edge of the arm 5, and by turning the screw inwardly, or outwardly, as the case may be, very accurate

adjustment of the arm may be made. Upon loosening the screw 14 the arm 5 may be turned to the right or to the left to accurately adjust the cylinder staff to the proper depth in the escape wheel 19; and when the staff is properly adjusted, the screw 14 will be tightened to keep the parts in their adjusted position.

By reference to the drawing it will be seen that the balance cock is secured on the upper end of the chariot hub and the chariot and the balance cock move in unison relative to the pillar plate.

We do not restrict our claims to the precise construction herein set forth, inasmuch as it is obvious that other suitable means for uniting the balance cock and the chariot to move in unison, may be used, and still remain within the scope of our invention.

Having fully described our invention, what we claim as new and desire to secure by Letters Patent is:

1. In a depth-adjusting device, the combination of a pillar plate having a trench adapted to accommodate a movable arm, also having a cylinder-staff opening, and a boss-opening; in combination with an arm having a boss extended through and rotative in the boss opening; a balance cock fixed on the boss of the arm; means for adjusting the arm in the trench of the pillar plate; and means for securing the arm in its adjusted position.

2. In a depth-adjusting device, the combination of an oscillative adjusting arm having a jewel adjacent to its free end; a balance cock fixed on the adjusting arm and having a jewel in line with the jewel of the adjusting arm; a cylinder staff having its pivot in the jewels of the adjusting arm and the balance cock; and an adjusting screw adapted to effect slight rotative movement of the adjusting arm on its axis.

3. In a depth-adjusting device, the combination of an oscillative adjusting arm having a jewel; a balance cock fixed on the arm and having a jewel in line with the jewel of the arm; a staff having its pivot in the jewels of the arm and the balance cock; means for accurate rotative adjustment of the arm; and means for securing the arm in its adjusted position.

4. In an appliance of the class described, the combination of an escape wheel; a cylinder staff coöoperative with the escape

wheel; a balance cock, an oscillative support for the cylinder staff and the balance cock; and means for rotating said oscillative support on its axis to vary the depth of engagement of the cylinder staff with the escape wheel.

In witness whereof we have hereunto

signed our names at Springfield, Illinois, this 16th day of February, 1920.

FRED R. COATS.
JEAN F. HARTWELL.
